UNITED STATES PATENT OFFICE

2,083,261

GAS HAMMER

Thomas C. Gray, Evanston, Ill., assignor to Barco Manufacturing Co., Chicago, Ill., a corporation of Illinois

Application March 7, 1936, Serial No. 67,593

11 Claims. (Cl. 123—7)

This invention relates to improvements in internal combustion hammers.

Heretofore internal combustion hammers having springs for returning the pistons have had such return springs mounted inside of the cylinder below the piston. The springs so located are subject to considerable of the heat generated in the cylinder by combustion and are therefore liable to deteriorate by reason of the effect of such heat. Furthermore, the return springs so confined are not conveniently accessible for replacement. Another disadvantage of such an arrangement is that the confining of the spring in the cylinder below the piston necessitates providing a cylinder of considerable length.

In accordance with this invention the piston return springs are mounted outside of the cylinder, thus making them more accessible, easier to keep cool, and making it possible to employ a shorter cylinder.

Various other objects and advantages of the invention inherently possessed by it will become apparent upon a perusal of the specification.

In the drawings:

25 Fig. 1 is a central vertical sectional view of one form of the invention, and

Fig. 2 is a central vertical section of another form of the invention.

Referring now to Fig. 1, the invention therein shown includes a cylinder 1 in which a piston 2 is disposed. The piston is provided with a striking portion 3 adapted, at the lower end of the stroke of the piston, to strike the raised portion 4 of an anvil 5 which transmits the blow to a tool 6 extending upwardly into the anvil. While a recess is provided in the anvil shown to receive the tool, it should be understood that a recess is not necessary as the bottom of the anvil may be otherwise shaped in the area in which it contacts with the tool.

The tool, which may be a drill, tamper, concrete breaker, or other similar device, is retained by a tool guide 7, abutting the lower end of an anvil housing 8 and held yieldably thereagainst by tension springs carried on tie rods whose upper ends are supported preferably on the handle ring, later described. These springs and tie rods may be similar to those disclosed in U. S. Letters Patent No. 1,997,072, issued April 9, 1935, to James A. Mould.

In hammers of this type heretofore constructed, the piston return springs have been positioned within the cylinder below the piston, usually between the piston and the anvil. The present invention contemplates mounting the return

springs outside of the cylinder. With this end in view, a rod 9 is connected in any suitable manner to the upper end of the piston and extends through the top of the cylinder, being provided on its upper end with a head 11 or some other suitable means for retaining the upper end of the return spring 12. The lower end of the spring 12 is preferably seated on another spring which may be termed a cushioning spring 13, being heavier and stronger than the long spring and serving to dampen the vibrations of the longer spring. The short cushioning spring surrounds a boss 14 on the top of the cylinder and is held against lateral displacement thereby.

The head 11 reciprocates in a guideway 15 which may be either a cylinder or of other suitable construction to guide and steady the rod 9 in its movements, and also to form a protective guard around the enclosed moving parts. The cylindrical guideway 15 of Fig. 1 is provided with a cover plate 16 having a central aperture through which a tool or rod may be introduced to depress the head and the piston for starting purposes. A keyway 10 cooperating with a key 20 prevents rotation of the head.

While other means of controlling the ignition for the hammer may be employed, it is preferred to operate the timer or interrupter from the head 11 which, for this purpose, is provided with a cam surface 18 at one side. As the head reciprocates with the piston, the cam follower 19 will press the plunger 21 outwardly to cause a spark across the terminals of the spark plug 22. During normal operation of the device, the piston will not rise as high as the position which it occupies in the drawings because of the resistance offered by the combustible charge in the cylinder above the piston.

The anvil housing and anvil contained therein serve to close the bottom of the cylinder and afford between the bottom of the piston and top of the anvil and housing a precompression space in which the combustible mixture will be compressed by the power stroke of the piston and while being compressed forced up into a plurality of vertical passages 23 and horizontal passages 24. Hence, when the top of the piston drops below the top of the recess 25 in the cylinder wall, the recess 26, also being in registration with the by-pass recess 25, may then enable the precompressed mixture to flow around through the by-pass up over the top of the piston ready to be compressed by the piston when the return springs raise the latter up again to fir-

ing position. An exhaust passage 27 is provided for exhausting the burned gases.

In this form of the invention it is preferred to support the fuel tank 28 solely on the anvil housing 8 in order that the fuel tank may be subjected to no more heat than necessary. Its inner walls are shaped to avoid contacting the vertical fins such as 29, 31 and others, not shown, which are provided on the cylinder. The exact manner of mounting this tank and the form of the carburetor employed for forming the mixture do not constitute a part of this invention, but reference may be had to the James A. Mould U. S. Patent No. 1,997,072, issued April 9, 1935, for a disclosure of one suitable form of mounting for the tank and construction of a carburetor. It is sufficient to call attention to the fact that the combustible mixture will preferably be introduced into the precompression space through an aperture 32.

Also the manner of securing the anvil housing rigidly on the bottom of the cylinder and the manner of yieldably supporting the tool guide 7 also do not constitute a part of this invention. 25 And again reference may be made to the above-mentioned Mould patent to ascertain how this may be done, if desired. It will be noted that in that patent the tension rods which retain the anvil housing and also yieldably support the tool 30 guide are themselves secured upon the handle ring and they may be so supported here.

The handles 33 and 34 by which the tool is held are secured to a handle ring generally designated as 35 which rests upon a shoulder 36 provided on 35 the cooling fin structure. This handle ring may be secured upon that shoulder in any suitable manner, for example, by the tension bolts just above referred to.

Fig. 2 shows another form of the invention, 40 differing from Fig. 1 only in the manner of operating the timing mechanism. The details of construction of this form of the invention, insofar as they resemble the form disclosed in Fig. 1, need not therefore be described. It suffices to state 45 that this form of the invention includes a cylinder 41, a piston 42, a rod 43 connected in any suitable manner to the top of the piston, return springs 44 and 45, and a head 46 secured in any suitable manner, as by threads, to the top of the 50 rod for holding the return springs under compression, as illustrated. In this form of the invention, the head 46 is not employed to actuate the timing mechanism.

The piston 42 is provided with a striking portion 47 which imparts the blow of the piston to 55 the anvil 48 which transmits the blow then to the tool 49.

A timing plunger 51 having a cam follower 52 riding in a groove 53 on the outside of the piston 60 wall will be thrust outwardly by the cam surface 54 provided at the lower end of the groove to cause a spark to occur across the terminals of the spark plug 55.

By removing the cover plate 56 and the spring 65 retaining head 46, the return springs may easily be replaced whenever desired, and the tension of the springs may be regulated by adjustment of the head on the rod or by the employment of shims.

The cylinder 51 operates as does the cylinder 15 of Fig. 1, both as a guide for the spring retaining head and also as a shield surrounding the springs.

It is contemplated that the fuel tank 28 will 70 be mounted on the anvil housing 59 in the same

or similar manner as is the fuel tank of Fig. 1, the fresh charges of fuel being admitted into the precompression space below the piston through an aperture 61.

It should be understood that the drawings and 5 specification disclose and describe merely two embodiments of the invention, but other variations of the invention are possible and are contemplated and included within the scope of the appended claims.

The invention above shown and described is 10 claimed as follows:

1. In an internal combustion power hammer, a cylinder, a piston therein, a spring mounted outside of the cylinder, and means operatively connecting said spring and piston for moving the piston under the influence of said spring, said means comprising a longitudinally movable rod on said piston.

2. A power hammer comprising a cylinder and 20 a piston therein, a spring mounted outside of the cylinder, and means operatively connected with the spring and with the piston for retracting the piston in the cylinder after each power stroke, said means comprising a longitudinally movable 25 rod on said piston.

3. In a power hammer, a cylinder and a piston therein, a spring mounted outside of the cylinder and substantially coaxial therewith, and means 30 extending through a wall of the cylinder connected with the piston and operatively connected with the spring for moving the piston in one direction, said means comprising a longitudinally movable rod.

4. In a power hammer, a cylinder and a piston 35 therein, a spring mounted outside of the cylinder, and means extending through one end of the cylinder connected with the piston and operatively connected with the spring for moving the piston in one direction in the cylinder.

5. In a power hammer, a cylinder and a piston 40 therein, a spring mounted outside of the cylinder, and means extending axially through said spring and operatively connected to one end thereof and further connected with the piston for moving the 45 piston in one direction in the cylinder.

6. In a power hammer, a cylinder and a piston 50 therein, a spring mounted outside of the cylinder, means operatively connected with the spring and with the piston for returning the piston toward one end of the cylinder, an ignition system for igniting a combustible charge in the cylinder, and means operated by the motion of said spring actuated piston returning means for controlling said ignition system.

7. In a power hammer, a cylinder and a piston 55 therein, a rod connected with the top of the piston extending through the top of the cylinder, and a spring mounted outside of the cylinder operatively connected with said rod and held 60 under compression thereby.

8. In a power hammer, a cylinder and a piston therein, a rod connected with the top of the piston extending through the top of the cylinder, a spring mounted outside of the cylinder operatively connected with said rod and held under compression thereby, an ignition system for igniting a combustible mixture in the cylinder, and means connected with said rod for controlling the spark in said system.

9. In a power hammer, a cylinder and a piston 70 therein, a rod connected with the top of the piston extending through the top of the cylinder, a spring mounted outside of the cylinder, means connected with said rod holding said spring under 75

compression, and means for varying the compression of said spring.

10. In a power hammer, a cylinder and a piston therein, a spring supported on the top of said cylinder and rising thereabove, and means connected with said piston and holding said spring under compression for returning the piston after each power stroke.

11. In a power hammer, a cylinder and a piston therein, a spring supported on the top of said cylinder and rising thereabove and adjustable means connected with said piston and holding said spring under compression for returning the piston after each power stroke.

THOMAS C. GRAY.
